UNITED STATES PATENT OFFICE.

JOHN T. HAY, OF UNION CITY, OHIO.

PITMAN.

1,100,732.

Specification of Letters Patent. Patented June 23, 1914.

Original application filed October 16, 1911, Serial No. 655,018. Divided and this application filed April 24, 1912. Serial No. 692,994.

To all whom it may concern:

Be it known that I, JOHN T. HAY, a citizen of the United States, residing at Union City, in the county of Darke and State of 5 Ohio, have invented certain new and useful Improvements in Pitmen, of which the following is a specification.

This invention is a division of my application for a patent for automatic take-up 10 for journal-boxes, filed October 16, 1911, Serial No. 655,018, and the object of this invention is to provide a pitman with adjustable journal-boxes at each of its ends, an automatic take-up and release for one set 15 of said journal-boxes, and means extending from the boxes at this last mentioned end to those at the other end of the pitman whereby the boxes at both ends of the pitman will be correspondingly adjusted.

20 I accomplish the above objects by the mechanism illustrated in the accompanying drawings, in which—

Figure 1 is a view in side elevation of a pitman embodying my invention. Fig. 2 is 25 a view on a larger scale of one end of the same rod shown in Fig. 1. Fig. 3 a view in longitudinal section of a pitman showing a modified form of my device, and Fig. 4 is a view on a larger scale of one end of a pit- 30 man having stirrups as shown in Figs. 1 and 2, but with a modification of some of the parts of the automatic take-up and release mechanism.

Like characters of reference indicate like 35 parts throughout the several views of the drawings.

3 is a connecting rod having heads 2, and stirrups 4 at each end which pass around two-part journal-boxes 5 and 6 to support 40 said boxes in operative position at their respective ends of rod 3. The stems of the stirrups 4 slide loosely in suitable channels in the expanded ends of the rod 3, and stems of the opposing stirrups lap each other and 45 are secured by bolts 7. The movement of one stirrup will correspondingly move the other so that when the journal-boxes become loose the tightening of those at one end will act on the stirrup to transmit movement to 50 the other stirrup and tighten its boxes.

8 is a pin or shaft mounted in the two brasses or box members 9 and 10. The outer face of the outer box member 10 is oblique to its adjacent sides as shown, and a taper- 55 ing wedge 11 is introduced between the

oblique box and stirrup. Liners α may be inserted at the ends of the boxes to fill out excess space.

A lever A is pivoted at 18 to the lower stems of the stirrup and has an extension 60 15 which bears against the shaft 8, and pivoted at 33 to the lower strap or stirrup 4 is the lever B having an extension 36 which bears against the shaft 8 at a point diametrically opposite the said bearing 15 from the 65 lever A. The two levers A and B are connected by a rod 38 pivoted at one end to the lever A and having its opposite end extended through a suitable opening in the lever B. This last end of the rod 38 is 70 threaded to receive a nut 39 to regulate the approach of levers A and B, to loosen or tighten the journals.

40 is a nut on the outer end of the rod 38. Between the nut 40 and the lever B is 75 a spirally wound spring 42, which acting through the rod 38 draws the levers A and B toward each other to keep their extensions 15 and 36 in contact with the shaft 8. Pivotedly mounted at C' in the upper end 80 of the lever B is a bent lever C having its outer arm slotted at d to receive a pin D which supports the tapering wedge 11. The inner and downwardly bent end of the lever C has a longitudinal slot e to receive a trans- 85 verse pin E. Standards F secured to the upper stem of the stirrup 4 have vertical slots f through which the pin E also passes and the projecting ends of the pin are provided with heads as shown in Fig. 2 to prevent the longitudinal withdrawal of the pin 90 from said slot. An upward movement of the pin E in slots f and e will transmit any pressure and movement from the pin E to the lever C nearer to the fulcrum of said 95 lever, thereby shortening the bent arm of the lever C and correspondingly increasing the travel of the outer arm of said lever. The attached wedge 11 will be raised with a correspondingly greater speed. When the 100 pin E is lowered in said slots f and e the bent arms of the lever C will be correspondingly lengthened causing the outer arm to move a less distance. The raising and lowering of the pin E in the slots f and e is 105 accomplished by the longitudinal movement of a bar G having a bent end in which is an oblique slot g through which the pin E also passes in the manner shown in Fig. 2. The bent end of the bar G rests upon the base of 110

the standards F and is slotted to loosely receive a bolt e which will hold the end of the bar down and at the same time allow it to slide past the bolt e.

- 5 The bar G rests upon a table h having sides h' extending down and secured to the upper stem of the stirrup 4. The sides h' are extended upwardly to form ears H between which a cam I is mounted to bear against the bar G. Mounted at the top of the lever A is a cam J which also bears against the top of the bar G. Both cams I and J are adapted to permit the bar G to move toward the pin E and will prevent the movement of said bar in the opposite direction. The cam I has an arm extension i and the cam J has a like arm extension j, both arms being on adjacent sides of their cams, and the two arms 15 are joined by means of a coiled spring K, the extension of which, acting through said arms, holds the two cams I and J in contact with the bar G. The construction however will permit the oscillatory movement of the lever A away from the lever B without taking the bar G with it, and it will also be noted that the action of the cam I at such times will positively prevent the movement of the bar G with the lever A. But upon 20 the return movement of the lever A, the cam J will lock the bar G to the lever A causing said bar to move with the lever A toward the pin E and it will then be noted that the action of the cam I will permit 25 this movement of the bar G toward the pin E. It will thus be seen that the bar G is capable of adjustment longitudinally toward the pin E but that it cannot be moved in the opposite direction.
- 30 Slidingly mounted upon the upper stem of the stirrup 4 below the table h is a bar L. A cam M is mounted on the table h and bears against the bar L in a manner to lock the bar against movement toward the pin E but permitting it to move in the opposite direction. The cam M has an arm m to which a spring m' is connected at one end, the other end of the spring being made fast to the upper stem of the stirrup 4, as 35 shown in Fig. 1. The bar L has a vertical slot through which the lever A passes, the slot being of sufficient length to permit of a limited oscillatory movement of the lever A, and mounted in a suitable socket in the bar L entering the slot and bearing against the lever A, is a spring N of less strength than the spring 42 on the rod 38. The tension of the spring N will be regulated by a set-screw n. As the shaft 8 will generally 40 be of soft iron or steel which will wear readily, I prefer to shrink a collar 44 of hardened steel around it for the extensions 15 and 36 to bear against.
- 45 The operation of my invention is as follows: Assuming that the journals 5 and 6

at both ends of the connecting rod have been made tight against their respective shafts or pins by the introduction of liners x, if necessary, and that a bearing at either end of 5 or 6 of the connecting rod has become 70 loose by wear, which, because of the stirrup connections loosens the journals at both ends of the rod, then, by the alternate push and pull of the connecting rod against the shafts at each revolution of the crank, the levers 75 A and B, tied together by the spring-tightened rod 38, will oscillate, and the bar G, by the action of cams I and J, will be moved toward the pin E raising the latter. This has a tendency to swing the lever C 80 around the pivot c' to lower the outer arm of the lever and lower the wedge 11. But this is immediately overcome by the swing of the lever B toward the shaft 8, toward which it is also drawn by the spring 42 on 85 the rod 38, and at this inward movement of the lever B the pin E becomes the pivot around which the lever C swings, and the resulting swing of the latter raises and tightens the wedge 11. The above oscillations of the levers A, B and C, will only 90 continue until the pin E has reached the point where it will raise the wedge 11 fast enough to take up all wear. When this occurs the levers A, B and C, cease to oscillate 95 but they will move only in the direction required to raise the wedge 11 sufficiently to take up the existing wear. The proper movement of the wedge is determined automatically as above described by raising 100 the pin E, but when the right position of the pin E is thus found, the operation of levers A, B and C, will continue to raise the wedge 11 as long as the relative rate 105 of wear on the several boxes remains unchanged. Should this again vary, the oscillatory movement of the said levers and the corresponding movement of the bar G to raise the pin E will again occur. The oscillatory movement of the levers A, B and C, 110 is occasioned by a wear on the journal-boxes at a faster rate than the wedge or key 11 is moved to take it up. The tightness of the boxes will be regulated by the tension of the spring 42, as regulated by the 115 nuts 39 and 40. Should the journals become too tight, as by the overheating of their shafts, the lever B will be moved outwardly by the expansion of the shaft thereby lowering the wedge or key 11 and loosening the boxes. By the cooling of the shaft 120 and its resulting shrinkage, the lever B will swing back by the action of the spring 42, and the wedge or key 11 will be raised and the journal tightened and a normal condition maintained until the journals become heated again. The bar L can only move toward the cam M, which movement will occur by the pressure against it of the lever A which will keep the spring N tight 130

against said lever and prevent the rattling of the parts of my device, and also keep the levers A and B from swinging on their pivots toward the wedge 11 by the wearing 5 away of the journal-members, thereby lowering and loosening the wedge 11 instead of causing the levers to oscillate by the action of the spring N against the lever A together with the lateral movement of the 10 shaft. This oscillatory movement advances the bar G and raises the pivotal point E thereby tightening the wedge by the action of the lever C. When by the wear of the 15 journal-boxes the bar L has reached the limit of its longitudinal movement it will be set back by manually releasing it from its cams and additional liners α will be added to tighten the boxes.

In the modification shown in Fig. 4 the 20 lever C' is inverted and the fulcrum is at E instead of at c' as in Fig. 2, which secures greater leverage in raising the wedge or key 11 and affords a more positive support for the latter. This modification also shows 25 detachable bearing shoes 50 against the collar 44 of the shaft 8 whereby the bearings against the collar may be readily renewed when they become too much worn for good service. In this modification also the 30 arm j of the cam J is moved by a compression spring k to tighten the cam. The spring k has its upper portion bearing against the arm j and its lower bearing against a shoulder extension from the lever A whereby the 35 spring will be carried by the lever A and will not be influenced by the oscillatory movement of the latter. In this modification also the arms i and m of the cams I and M are pressed in a direction to tighten said 40 cams by a spring K'. Otherwise the mechanism is substantially as described and shown in Fig. 2.

In the modification shown in Fig. 3 the 45 pitman is made hollow to receive a push bar 52 which terminates at each end against the inner boxes at the opposite ends of the pitman. The stirrups 4' are not connected as shown in Figs. 1, 2 and 4, but are bolted rigidly to the ends of the pitman, in the 50 usual manner. The push-bar 52 will equalize the pressure of the journal-boxes against their shafts at both ends of the pitman substantially in the same manner that this was accomplished by connecting the two-end 55 stirrups.

Having thus fully described my invention, what I claim as new and wish to secure by Letters Patent of the United States, is—

1. A pitman, end journal boxes, each in 60 a plurality of members at least one of which is movable, adjustable means to limit and vary by adjustment the tightness of the

members on their shaft, automatic means operated by the expansion and contraction of the shaft and journal members to secure 65 and constantly maintain the tightness of the members at this limit, and means connecting the journal boxes of the two ends of the pitman whereby a movement of one will correspondingly move the other. 70

2. The combination, in a pitman, of a pair of shafts, one at each end of the pitman, a plurality of box members for each shaft at least one of which for each shaft is movable and one of which movable box 75 members has an oblique end, holders in which the box members are mounted, a wedge in the holder contacting with the oblique box member to tighten all of the members, means for automatically moving the wedge at any 80 variation from a predetermined pressure of the box members against their shafts to maintain a uniform tightness of journal boxes, means to prevent the movement of the wedge in a direction to loosen it, and 85 means for connecting the box members at the two ends of the pitman to correspondingly move the box members at both ends of the pitman.

3. The combination in a pitman of a pair 90 of shafts one at each end of the pitman, journal boxes for each shaft in a plurality of members at least one of which is movable, means to secure a minimum shaft pressure of said members, automatic means operated 95 by the expansion and contraction of the shaft and journal members to secure and constantly maintain said minimum pressure, a stirrup at each end of the pitman to hold the journal members, means for connecting 100 the two stirrups whereby a movement of one will correspondingly move the other, and means for varying the distance between a movable journal member and the adjacent stirrup-end. 105

4. In a pitman, a rod, a pair of shafts, journal boxes for the shafts at the ends of the rod each in a plurality of members at least one of which is movable, a tightening wedge, stirrups holding the respective journal members and wedge, means contacting with one of the shafts to move the wedge by the expansion and contraction of said parts, and elastic means for maintaining the contact of the journal-members against the 115 shaft.

In witness whereof, I have hereunto set my hand and seal at Indianapolis, Indiana, this 7th day of March, A. D. one thousand nine hundred and twelve.
